CALIFORNIA.

DRILL.

Application filed December 26, 1923. Serial No. 682,763.

The present invention relates to improvements in drills such as are used for the boring of wells or the like and has particular reference to a reciprocating drill of the 5 character described. It is particularly proposed in the present invention to show a construction in which a reciprocating drill bit cooperates with the casing in regulating the flow of water which is admitted under pressure through the bit to the surface attacked by the bit. The details of construction and further advantages of our device will appear as the specification proceeds.

The preferred forms of our invention are 15 illustrated in the accompanying drawing in which Figure I shows a vertical section through one form of our drill, while Figure II shows a vertical section through a second form of drill. While we have shown 20 only the preferred forms of our invention, it should be understood that various changes or modifications may be made within the scope of the claims hereto attached without departing from the spirit of the invention.

25 In the form illustrated in Figure I, our drill bit (1) which may be of any conventional form, is threaded into the lower end of a piston (2), as shown at (3). The latter piston is in threaded engagement with a series of tools or connecting members of which 30 only one is shown, which in the trade is known as a jar (4). The series of tools connect with a suitable means for reciprocating the piston which is not shown in the drawing 35 since it is well known in the art.

The piston reciprocates in a casing (6) which latter is unsupported at its lower end as indicated, the casing being suspended from its upper end by any suitable means 40 not shown, and successively lowered as the way is cleared for the same by the bit. The piston is provided with suitable piston rings (7) engaging the inner wall of the casing and making a water-tight connection with 45 the same. The bit is perforated vertically, as shown at (8) and holes (9) are provided in the top of the piston, allowing water introduced into the casing to pass through the piston and the perforations (8) in the bit 50 to the bottom of the well, so as to loosen and wash away the soil formation as the same is cut up by the drill in operation.

The principal idea of the present invention is the provision of the piston which 55 guides the water introduced under pressure

into the casing 6 for passing through the drill bit to return on the outside of the casing so as to constantly wash out a clear space around the casing and to allow the casing to descend when lowered from above as 60 the well is deepened, the débris being forced up on the outside of the casing.

The same idea is carried out in the form shown in Figure II, in a slightly different manner. Here the bit (1a) is screwed into 65 a connecting member (11), which latter is secured to a series of tools of which only one (12) is shown in the drawing. The connecting member (11) is provided with a collar (13) at its upper end and is hollowed, as 70 is shown at (14) to permit water under pressure to be carried to the bottom of the well through a nozzle (16) in the drill bit. A cylindrical member (17) of flexible material 75 is provided in the casing (18), and allows the connecting member (11) to reciprocate therethrough, while making water-tight connection with the said connecting member, as well as with the inside of the casing, so as to prevent water from rising within the casing. 80 When connecting member (11) reciprocates during the operation of the drill, the collar (13) strikes the flexible member (17) and gradually forces the same downwardly relative to the casing 18 at the same rate of speed 85 at which the well is deepened.

The principal idea of this form again is to allow water to be introduced into the casing under pressure and to enter into the bottom of the well through the hollow connecting member (11) and the nozzle (16), so as 90 to wash away the débris and to force the same to the outside of the casing for discharge at the top of the well and to provide a clear hole, for the lowering of the casing 95 and drill bit as the work progresses.

We claim:

1. In a well boring outfit a casing extending into the bore hole and spaced therefrom, a drill reciprocable within the casing and 100 having a tubular connecting stem of reduced diameter, a packing ring fitting within the casing surrounding the reduced stem frictionally slidable both on the reduced stem and within the casing, and means for directing water from within the casing above the ring through the drill for overflow outside of the casing.

2. In a well boring outfit a casing extending into the bore hole and spaced therefrom, 105

a drill reciprocable within the casing and having a tubular connecting stem of reduced diameter, a packing ring fitting within the casing surrounding the reduced stem frictionally slidable both on the reduced stem and within the casing, means for directing water from within the casing above the ring

through the drill for overflow outside of the casing, and means actuated by reciprocation of the drill for progressively forcing 10 said ring downwardly relative to the casing as the hole is deepened.

BENJAMIN B. DUDLEY.
EDWARD R. DUDLEY.
